UNITED STATES PATENT OFFICE.

JAMES F. WINCHELL, OF SPRINGFIELD, OHIO.

FORGE.

SPECIFICATION forming part of Letters Patent No. 298,718, dated May 13, 1884.

Application filed September 7, 1883. (No model.)

To all whom it may concern.

Be it known that I, JAMES F. WINCHELL, a citizen of the United States, residing at Springfield, in the county of Clark and State of Ohio, have invented certain new and useful Improvements in Forges; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a representation of an end elevation of the forge. Fig. 2 is a sectional plan view. Fig. 3 is a detail view of the grip-clutch and rim-flange gear-wheel, and Fig. 4 is a view of the lever-joint.

This invention has relation to forges and furnaces, either portable or stationary; and it consists in the construction and novel arrangement of devices, as will be hereinafter fully described, and particularly pointed out in the claims appended.

Referring by letter to the accompanying drawings, *a* designates the top plate of the forge. The top plate, *a*, is mounted on legs *c*, suitably braced to give it strength.

d designates a fan-case secured to the top plate, or in any other suitable place, which carries the fan *e* on the fan-shaft *f*.

g is a band-wheel on a pinion-shaft, *h*, and is connected by a belt to the fan-shaft.

i designates a bracket secured to the legs of the forge, and furnishes the bearings for the pinion-shaft and the rim-flange gear-wheel *k*. The teeth of the rim-flange gear-wheel *k* engage a pinion, *l*, on the pinion-shaft

h. The wheel *k* is operated by a swinging grip-clutch, *m*, the jaws of which engage the rim-flange *n* of the wheel *k*, the swinging grip-clutch being operated by a lever, *o*, fulcrumed to the side of the forge, and connected to the swinging grip-clutch in any suitable manner, as by the rod *p* and knuckle-joint *q*.

Having thus fully described my invention, what I claim as new, and desire to secure by Letters Patent, is—

1. In a forge, the combination, with the fan and its shaft, of the band-wheel and belt connecting said wheel with the fan-shaft, the pinion *l*, journaled in the adjustable bracket *i*, and the rim-flanged gear-wheel, with mechanism for operating the same, substantially as specified.

2. In a forge, substantially as shown and described, the combination, with the rim-flanged gear-wheel *k*, of the grip-clutch *m*, consisting of an arm journaled to the axle of said gear-wheel, and extending downward to the periphery thereof, where it is pivotally connected with a swinging arm provided at its upper end with inwardly-projecting jaws for gripping the flange, and at its lower end with a slot for connecting, by means of the knuckle-joint *q*, with the bent rod *p*, which is connected with the lever *o*, whereby motion may be communicated to mechanism for operating the fan, as and for the purpose set forth.

In testimony whereof I affix my signature in presence of two witnesses.

JAMES F. WINCHELL.
